Robert L. Epstein(57) **CLAIM**

The ornamental design for a beverage dispenser, substantially as shown and described.

DESCRIPTION

FIG. 1 is a top front perspective view of a beverage dispenser showing my new design;

FIG. 2 is a bottom rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures indicate parts of the beverage dispenser which are not part of the claimed design.
